SWAGING MACHINE

Leo Robbins, New York, N. Y., assignor to Roberts
Manufacturing Co., New York, N. Y.

Application September 25, 1943, Serial No. 503,790

18 Claims. (Cl. 29—208)

1

This invention relates to swaging machines wherein a member which encloses a second member is adapted to be fastened to the second member by the application of pressure. Thus, for example, the hub on the upper end of the cannula of a hypodermic needle is swaged thereon.

It is the principal object of this invention to provide a completely automatic machine which requires the services of an operator only to feed the parts to be fastened together. Thereafter the entire action consisting of the steps of moving the parts to swaging position, performing the swaging operation, releasing the parts from the die and finally withdrawing the swaged members and depositing them in a suitable receptacle, are all performed automatically in the stated sequence.

It is a further object to provide a rotatable table in which are positioned the parts to be swaged, said table being fed step-by-step to move the parts to the swaging position, and then applying the swaging pressure in such manner as not to strain the table. For this purpose, I provide means for applying the pressure not merely to one side of the table in the swaging position, but to both sides thereon in such manner that the pressures equalize, and thus the swaging pressure is applied to the table without straining or twisting the table.

It is a further object of my invention to provide means for supporting the article to be swaged in the table in such manner that when the swaging pressure is applied at the top and bottom of the table, the article will be able to adjust its position for variations in position and variations in length of the article itself. For this purpose I provide means whereby the article is supported in the table in the swaging position solely by friction means, which can be overcome by swaging pressure.

Still another object of my invention is to provide means for applying the swaging pressure through a toggle mechanism which can employ a minimum length of toggle lever while at the same time giving the maximum movement of the swaging means in a predetermined time interval. Thus, with a minimum length of toggle lever, I am enabled to withdraw the punch from the table in only a fraction of the cycle during which the table is stationary.

Still another object of my invention is to provide means for performing a plurality of steps in withdrawing and discharging swaged articles, said means including a tubular member for per-

2

forming one function, and a rod within the tubular member for performing another function, together with separate levers for operating the tube and the rod independently. It is an object of this invention to permit the rod to perform its function without tending to operate the tube to such degree as to call for strong restraining means on the tube. For this purpose I pivot the rod operating lever on the tube operating lever in such manner that upward movement of the rod results in a downward reaction on the tube operating lever, whereby the movement of the rod itself provides means for opposing the movement of the tube.

Still other objects and advantages of this invention will become apparent in the following detailed description thereof:

In the accompanying drawings, Fig. 1 is a plan view of one embodiment of my invention.

Fig. 2 is a side elevation of the Fig. 1 machine with parts broken away and parts sectioned.

Fig. 3 is a vertical section through the tube and rod element shown in Fig. 2.

Fig. 4 is a section taken substantially on the line 4—4 of Fig. 2.

Fig. 5 is a section taken substantially on the line 5—5 of Fig. 1.

Fig. 6 is an enlarged section of a portion of the Fig. 5 device.

Fig. 7 is a section taken substantially on the line 7—7 of Fig. 1.

Fig. 15 is a section taken substantially on the line 15—15 of Fig. 14.

Fig. 16 is a section taken substantially on the line 16—16 of Fig. 14.

Fig. 17 is a section taken substantially on the line 17—17 of Fig. 4.

55 The following description of the automatic

swaging machine relates to the swaging of hubs on hypodermic needles, but it will be understood that this is for purposes of illustration only, and it will become quite apparent from the description that the invention is applicable generally to the swaging of any similar articles, and in fact, wherever one article encloses another and is to be fastened thereto solely by pressure.

The device comprises a table 10 having a plurality of supports 11 mounted therein adjacent its outer circumference at uniformly spaced intervals, each of said supports 11 being adapted to hold the articles to be swaged, in this case, a hypodermic needle and a hub to be fastened to the upper end thereof. Such needle and hub are shown in several of the figures, as for instance, Figs. 6, 7, 8 and 9, all of which show a needle 12 and a hub 13. Each of said supports 11 has a tubular opening 15 extending vertically therethrough, slightly larger than the needle so that the needles can readily be inserted within the supports. The needles drop into the holes 15 until they rest upon a circular track 17 formed in the fixed support 18 in which the table is supported for rotation. An operator, sitting at the upper left in Fig. 1 inserts the needles and then places a hub 13 on each needle, each hub having a shoulder 20 (see Fig. 6) adapted to rest on the upper end of the needle. The hub has a circular converging portion 21 which surrounds the upper end of the needle, and it is this portion which is to be swaged to the upper end of the needle, that is, fixed thereto, solely by pressure. The hub has a central opening 22 in alignment with the opening in needle 12, and also has an upper portion 23 provided with a hollow, slightly downwardly tapering interior 24.

Referring to Fig. 6, it will be seen that the upper end of each support 11 is provided with a die 25 having a downwardly tapering portion 26 adapted to receive the downwardly tapering portion 21 of the hub 13. It will be seen that if the needle is held stationary within the support 11, and sufficient pressure is applied to drive the hub 13 into the die 25, the portion 21 of the hub will be pressed firmly around the outer surface of the upper end of the needle 12 so as to be permanently fixed thereto.

The operator having inserted the needle and hub in each support 11 after the table has passed the station marked "S" in a clockwise direction, it is then the function of the machine to feed each support successively to the swaging position indicated at C, thence to position D where the hub is released from the tight pressure in the die 25, and then to position E where the swaged articles are lifted out of the support and deposited in a suitable receptacle.

For carrying out the above automatic steps, it is first necessary to drive the table in a step-by-step circular motion so that each support 11 will first pass in front of the operator who supplies the articles to be swaged, and will then be carried successively to swaging position C, releasing position D, and lifting and discharging position E. For driving the table in the step-by-step circular motion, the table may be mounted on a shaft 30 journaled in the fixed support 18 and adapted to be driven from any suitable source of power, such as the belt and pulley 31, 32. Pulley 32 operates the main drive shaft 33 provided with a worm 34 at its inner end, said worm meshing with a worm wheel 35 having a member 36 concentric therewith, said member carrying a planetary pin 37 designed to engage, once during each revolution

of gear 35, the star wheel 39 fixed concentrically to the shaft 39 on which the table 10 is mounted. Thus, once for each revolution of worm wheel 35, the table 10 will be moved one step corresponding to the angular distance between the supports, said distance being that between stations C and D, and between stations D and E.

In order to define the steps so that the table will be positioned exactly in operating position at each step, there is provided a defining pin 40 (see Figs. 2 and 5), which is normally spring-pressed upwardly by means of a spring 41 in the fixed support so as to tend to move the upper tip 42 of the pin into a corresponding detent 43 in the table. When pin 40 enters detent 43 the table is in the proper operating position. When the table is to be moved to a new position, the pin 40 is withdrawn by means of a lever 45 pivoted at 46 on the fixed frame, and having a roller 47 at one end adapted to be engaged by the cam portion 48 of a cam fixed upon the shaft 38 which carries the worm 34. The cam 48 is so positioned that when the operations at C, D and E are completed, and the table is to be moved to the next step, said cam will engage roller 47 to lift that end of the lever and depress the other end of the lever which is in the form of a fork 49 engaging lateral arms 50 on the pin 40 to depress the pin against the action of spring 41 and withdraw the tip 42 from the detent 43. As soon as the star wheel has moved the table to the next step, the cam 48 ends, allowing lever arm 45 to drop and fork 49 to rise, thus permitting the tip 42 to enter the next detent 43. The table is thus moved step-by-step through the proper angular distance, and each step is defined by the defining mechanism just described to bring the supports 11 into the proper working position.

Let us take for example, the support 11 which is in position A, and follow through the operations on this particular needle and hub. In position A the needle still rides upon the supporting track 17 in the fixed support. However, when the needle is moved into swaging position, the track cannot be used because during the swaging operation the hub is moved downwardly. The needle must also be able to move downwardly, otherwise it would bend. Therefore, the fixed support at the lower end of the needle provided by track 17 is replaced by a frictional means permitting movement of the needle in its support. For this purpose, the table 11 carries pins 52, one for each support. Each pin 52 (see Fig. 6) extends through the support but is normally held out of engagement with the needle by reason of the fact that the pin is connected to a spring member 53 fixed to the periphery of the table at 54 and having a roller 55 at its outer end. As the table carries each needle into position A, we see that it is but two steps away from the swaging position, and therefore, as the table moves from position A to position B, which is the last position having the support 17, the rollers 55 pass under a cam member 56 which presses the springs against the periphery of the table 10 and forces the pins 52 into engagement with the needle 12 within the support 11 in position B. As the table moves the needle from position B to position C, it will be seen that since the track 17 ends before position C, the needle is held in the support solely by the frictional engagement of pin 52 with the needle 12. The cam 56 extends far enough so that the pins 52 remain in engagement with the needle until after the needle has left position C, that is, until after it has been swaged, in which

case it is firmly held by reason of the fact that the hub 13 has been pressed tightly into engagement with the upper end of the needle. Thereafter, it is no longer necessary to maintain the pins 52 in frictional engagement with the needle, and springs 53 are allowed to extend themselves to their natural position to withdraw the pins 52.

The needle 12 held frictionally by pin 52 in the support 11 after leaving position B, and loosely supporting its hub 13, is now moved into the swaging position C. In this position the table 18 is cut away so that pressure may be applied to the upper and lower ends 11' and 11'' of the support 11. The support 11 extends below the bottom of table 10, and the hub 13 extends above the top of table 10 so that pressure may be applied at both ends without engaging the table. For applying the swaging pressure there may be provided two plungers, an upper plunger 60 and a lower plunger 61. The upper plunger 60 may be provided with a punch 62 adapted to enter the hollow interior 24 of the hub 13. The punch 62 also tapers downwardly so as to enter within the downwardly tapering interior 24 of the hub. It will be seen that if pressure is applied simultaneously by both plungers 60 and 61 at opposite ends, the lower portion 21 of hub 13 will be driven further and further into the decreasing cavity 26 in the die 25 until portion 21 is pressed into firm engagement with the needle 12.

The means for applying pressure to the plungers 60 and 61 is such that the pressures on these plungers are equal, and therefore the pressures on opposite sides of the table 10 are equal, and thus, the table is not subjected to any twisting stresses and strains which would be highly injurious in this type of machine. Such equal pressures are obtained by means of two levers 63 and 64 pivoted on the fixed support at 65 and 66 respectively, said levers having their inner ends 67 and 68 in engagement with the plungers 60 and 61 respectively. It will now be seen that if pressure is applied between the outer ends of the levers, said pressure will be equally distributed between the two levers, that is to say, the arrangement of two freely pivoted levers constitutes a self-equalizing arrangement.

For applying pressure to the outer ends of levers 63 and 64, there may be provided a toggle consisting of two links 70 and 71, the link 70 comprising several parts to be described hereinafter, and pivoted to lever 63 at 72, while the link 71 is pivoted to the lever 64 at 73. The links are pivotally connected at 74. They are shown in alignment, that is, in their pressure applying position, but the toggle may be broken by pulling pivot 74 toward the right in Fig. 5. The means for applying pressure to the pivot 74 to straighten and break the toggle may take the form of a link 75 pivoted to the pivot 74, and having at its upper end a plate 76 to which is fixed a plate 77 (see Figs. 12 and 13). For operating the link 75 to the right to break the toggle, there is provided a mutilated eccentric 79 on driving shaft 80, said eccentric operating within a slot or cavity 81. As the shaft 80 rotates, the eccentric 79 will press against a projection 83 fixed to the outer end of plate 77 within the cavity 81, and thus force the plate 77, and hence link 75, to the right. This will break the toggle because pivot 74 will be pulled toward the right. It is desirable that the link 71 be as short as possible, for thereby there is obtained the maximum angular displacement of said link for a given linear movement of the pivot 74 toward the right. Therefore it is desir-

able that the movement of pivot 74 to the right be held to the minimum necessary to accomplish breaking of the toggle and to yield sufficient movement of end 67 to permit spring 86 to lift the plunger 60 and the punch 62 to the necessary height to clear the hub in the next succeeding support 11. In order to keep the link 71 as short as possible, the eccentric 79 is provided with a mutilated or cut off portion 90 so that when point 91 at the beginning of said mutilated portion reaches the projection 83, no further outward movement of plate 77 will take place. If the eccentric were not so mutilated, there would be continued movement of plate 77 until point 92 reached the projection 83, and this would give a much larger throw of the eccentric, and would necessitate a longer link 71, and hence, enlargement of all of the parts to yield the same movement of end 67 of lever 63 in the given time interval.

The eccentric 79 thus moves the plate 77 and link 75 to the right only the distance necessary to cause the desired degree of movement of the toggle to cause plunger 60 to clear the oncoming hub. This is due to the mutilated portion 90, but by reason of this mutilated portion, it would be difficult or almost impossible to rely upon this same eccentric 79 to force the plate 77 and link 75 toward the left. Therefore, I provide upon the same eccentric 79, two outer plates 93 and 94 which are not connected to the plate 76 of link 75, but which may abut against it. The portions 95 of eccentric 79 on which are positioned these plates 93 and 94 are completely circular, and therefore, will withdraw the plates 93 and 94 toward the right a further distance than plate 77 is withdrawn toward the right (see Fig. 12). However, while the projection 83 of plate 77 is riding in the cut off or mutilated portion of eccentric 79, the eccentric portions 95 are starting to move the plates 93 and 94 toward the left, and these plates 93 and 94 will come into abutting engagement with the plate 76 just at the time that the end 91 of the mutilated portion reaches the projection 83. Thereafter continued rotation of the eccentric portions 95 will move plates 93 and 94 toward the left to accomplish the straightening of the toggle and the application of the pressure to the levers 63 and 64, and hence, to the plungers 60 and 61.

The shaft 80 (see Figs. 2 and 4) may be driven from the driving source 31, 32 by any suitable driving connections such as the worm 98 and the worm wheel 99, the latter being fixed to the shaft 80.

It will be understood that slight variations may occur in the distance between the plungers 60 and 61 due to the slight variations in the length of the needle and hub, and if the pivots 72 and 73 on levers 63 and 64 were always moved apart the same distance when the toggle was straightened, and the plungers 60 and 61 always moved together the same distance, there would result unequal pressures, and in some cases, might even result in destruction of the swaged articles due to excessive pressure. Therefore I provide means in the link 70 for a certain amount of lost motion when a predetermined pressure between the plungers 60 and 61 has been exceeded. For this purpose the link 60 is formed in two parts, the lower part having a rod 100 slidable in a sleeve 101, the part 100 having a lower shoulder 102, and the part 101 having a screw-threaded nut 103. A heavy spring 105 is positioned between the nut 103 and the shoulder 102 to keep the parts nor-

normally spread apart with a predetermined tension. It is only when this tension is exceeded by pressure generated between plungers 60 and 61 that any movement will take place between the rod and the sleeve, the rod moving inwardly within the sleeve. The rod may carry at its upper end a stop 106 slidably within a bore 107 in the sleeve 101 to limit the effective length of the link 60. The tension of spring 105 may be regulated by screwing the nut 103 up or down on sleeve 101 by means of the screw thread arrangement 110.

Since the levers 63 and 64 and the pressure applying mechanism in the form of the toggle constitute a floating assembly to the extent that it is movable around pivots 65 and 66, I may provide a spring pressed plunger 111 within a fixed cylinder 112 with a spring 113 to press it upwardly into engagement with the outer end of lever 64. This serves not only to support the floating linkage, but also to release the plunger 61 when the toggle is broken.

The hub having been swaged on to the upper end of the needle in position C, and the plunger elements 60 and 61 having been withdrawn from engagement with the hub and the lower end of the support 11, the said support carrying the swaged needle and hub is ready to be moved to position D. During its movement to this position it is the function of the apparatus to release the hub 13 from its tight engagement within the die 25 into which it has been pressed by the plunger 60 and the punch 62. For this purpose I cause the movement of the table itself to effect such release of the hub and its needle from the die. Therefore I provide upon the fixed support, in the line of movement of the hub 13, a pair of spaced, similar inclines 120 formed in a bracket 121 supported on a frame 122 fixed to the fixed frame 18. These inclines (see Fig. 10) are so positioned that the aperture 123 between them is in the line of movement of the portion of the hub 21 just above the die 25. This portion of the hub therefore enters the aperture 123 and rides up the incline as the table rotates, thus forcing the hub out of the die until the hub rides on the upper surface 125 of the inclines (see Figs. 8 and 9).

The swaged hub having now been released from its jammed position in the die, it is ready to be discharged from the support 11 in the table, and deposited in a suitable receptacle. This is accomplished when the respective support has moved to position E. In this position it is necessary for gripping fingers to engage the hub, lift the hub and needle out of the support 11, and deposit it in the receptacle. Since the gripping fingers must ordinarily be out of the way when the hub moves into position E, it will be understood that the following operations must be accomplished: The normally open gripping fingers 130 are in the dotted line position shown in Fig. 1, and must first be swung into the full line position, lowered, caused to grip the hub, raised, swung again to the dotted line position and opened to release the needle and hub. All of these movements are accomplished in the interval between steps of the table. In order to accomplish all of the above movements, I provide a pair of gripping fingers 130 (see Fig. 14), said fingers forming the outer ends of a pair of levers 131 pivoted at 132 and having their outer ends normally operated by means of a toggle comprising a pair of links 133 pivoted to levers 131 at 134, and said links 133 being pivotally connected at

their other end at 135 to an operating link 136 which, when drawn to the right, will open the toggle, and hence open the fingers 130 against the action of springs 137. For maintaining the fingers 130 normally open, the link 136 is normally drawn to the right by means of a bell crank 140 pivoted at 141 within a housing 142, said bell crank being connected to link 136 at 143, and having its other end normally operated in a counter-clockwise direction by means of a rod 150 normally pressed upwardly (by means to be described hereinafter) to swing the bell crank in a counter-clockwise direction. This maintains the fingers 130 normally open. The said fingers are also maintained normally raised above the table 10 by a distance in excess of the length of the hub and needle, and for this purpose the housing 142 is fixed to a sleeve 152 within which the rod 150 operates, and the sleeve 152 is also maintained upwardly against the action of a spring 153 by means to be described hereinafter.

The means for maintaining the rod and sleeve normally in elevated position, in which position the fingers 130 are open, is shown in Fig. 2, and comprises a set of cams 155 and 156 mounted upon the shaft 89 and engaging one end of a pair of levers 157 and 158. Lever 157 is pivoted on the fixed frame at 159 while lever 158 is pivoted on lever 157 at 160. The inner end 161 of lever 158 engages the rod 150 while the inner end 162 of lever 157 may take the form of a fork engaging pins 163 on the sleeve 152. It will be apparent by reason of the pivoting of lever 158 on lever 157 at 160 that when lever 157 moves around its pivot 159, the lever 158 will be carried up and down together with lever 157, and therefore, the rod 150 will move up or down simultaneously with sleeve 152. However, the lever 168 can pivot around its pivot 160 independently of any movement of lever 157 in order to operate the rod 150. Therefore, it is possible to design the cams 155 and 156 to give the following sequence. The end 162 of lever 157 is normally held raised, which also raises rod 150 and keeps jaws 130 open. When the housing 142 is swung from the dotted line position to the full line position shown in Fig. 1 (by means to be described hereinafter), the housing 142 is lowered by moving end 162 downwardly. This moves rod 150 downwardly also, but since there is no relative movement between rod 150 and sleeve 152, the jaws 130 remain open. When housing 142 has reached its lowermost position wherein the jaws 130 straddle the hub in position E, the rod 150 is given an independent movement downwardly relative to the sleeve 152, and this permits springs 136 to close the toggle and cause the members 130 to grip the hub. The cam 155 then operates on lever 157 to raise sleeve 152, rod 150 and housing 142 until the hub and needle clear the table, but since there is no relative movement between rod 150 and sleeve 152, the jaws 130 remain closed on the hub. Then the housing 142 is swung to the dotted line position shown in Fig. 1, and after this position is reached, rod 150 is moved upwardly relative to sleeve 152 to operate the bell crank 140 to the dotted line position in Fig. 7, thus opening the toggle and releasing the jaws 130. The swaged hub and needle then drop into a suitable receptacle positioned outside the path of movement of the table.

From the above description it will be seen that by pivoting lever 158 on lever 157, relative movement between the rod 150 and the sleeve 152 is accomplished without the necessity of providing strong restraining means, that is, a strong re-

straining spring on sleeve 152. Such a strong retaining spring would necessitate heavier operating mechanism for operating lever 157. By pivoting lever 158 on lever 157 it will be seen that any upward movement of the rod results in a downward reaction on the sleeve so that the very movement of the rod itself provides a restraining force which prevents the sleeve from following along with the rod, and thus, obviates the necessity of strong restraining means on the sleeve. Only a light retaining spring 153 is therefore employed.

For accomplishing the rotation of the housing 142 from the dotted line position to the full line position in the above sequence, there may be mounted on the shaft 80 an eccentric 170 (see Fig. 17), which has connected thereto a connecting rod 171 (see Fig. 4), which is pivotally connected at 172 to a bell crank 173 fixed to the sleeve 152. The eccentric 170 is so positioned as to accomplish the rotation of the sleeve 152 between the dotted line and full line positions shown in Fig. 1 in the sequence described above, which may be summarized as follows: The housing 142 is in raised position with the jaws 130 open as shown in dotted lines in Fig. 1. The housing is first swung from dotted line position to full line position in raised position with the jaws 130 open; the housing 142 is lowered with the jaws open until the jaws straddle the hub in the support 11; the jaws 130 are closed on the hub; the housing 142 is raised with the jaws grasping the hub and lifting the hub and needle out of the support to the position shown in Fig. 7; the housing is swung to the dotted line position shown in Fig. 1 with the jaws closed; finally the jaws 130 are opened to release the hub and needle.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a swaging machine having a movable table and a support mounted in said table, said support being adapted to carry the articles to be swaged, characterized by means for swaging articles by the application of pressure without introducing stresses and strains in the table due to twisting moment, said last named means including movable members, one member engaging each end of the support, and means for applying equal pressure to said movable members.

2. In a swaging machine having a movable table and a support mounted in said table, said support being adapted to carry the articles to be swaged, characterized by means for swaging articles by the application of pressure without introducing stresses and strains in the table due to twisting moment, said last named means including movable members, one member engaging each end of the support, and self-equalizing means for applying equal pressures to said movable members.

3. In a swaging machine having a movable

table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and means for applying pressure between the other arms of said levers, whereby equal pressures will be applied to opposite ends of said support.

4. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support.

5. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including lost motion means for taking up pressures between said lever arms in excess of a predetermined pressure.

6. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including resilient lost motion means for taking up pressures between said lever arms in excess of a predetermined pressure.

7. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other

lever being operatively connected to the other end of said support, and toggle means connected between the other arms of said levers for applying pressure therebetween, whereby equal pressures will be applied to opposite ends of said support, said toggle means including lost motion means for taking up pressures between said lever arms in excess of a predetermined pressure, and means whereby the degree of said predetermined pressure may be varied.

8. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including a pair of toggle links, one of said links having lost motion means for taking up pressures between said lever arms in excess of a predetermined pressure, said lost-motion means comprising two relatively movable parts, resilient means interposed between said parts, and means for varying the resistance offered by said resilient means whereby the degree of said predetermined pressure may be varied.

9. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including a pair of toggle links, an operating link connected to said pair of links, one of said pair of links being relatively short to give maximum angular movement for a given linear movement of the operating link, and actuating means for said operating link including an eccentric and means whereby said eccentric is effective for only an operation of the total throw thereof to permit the use of said relatively short link.

10. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including a pair of tog-

gle links, an operating link connected to said pair of links, one of said pair of links being relatively short to give maximum angular movement for a given linear movement of the operating link, and actuating means for said operating link including an eccentric and means whereby said eccentric is effective for only an operation of the total throw thereof in the direction for rendering the toggle ineffective to permit the use of said relatively short link.

11. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including a pair of toggle links, an operating link connected to said pair of links, one of said pair of links being relatively short to give maximum angular movement for a given linear movement of the operating link, and actuating means for said operating link including an eccentric and a projection connected to said operating link and adapted to engage said eccentric, said eccentric having a cutout portion whereby the eccentric engages said projection for only a portion of the total throw thereof in the direction for rendering the toggle ineffective to permit the use of said relatively short link.

12. In a swaging machine having a movable table and a support mounted in said table, said support being adapted to carry the articles to be swaged, characterized by means for swaging articles by the application of pressure without introducing stresses and strains in the table due to twisting moment, said last named means including a pair of pivoted levers, one arm of one lever being operatively connected to one end of said support, the corresponding arm of the other lever being operatively connected to the other end of said support, and toggle means connected between the other arms of said levers for applying pressure therebetween, whereby equal pressures will be applied to opposite ends of said support, said toggle means including a pair of toggle links, an operating link connected to said pair of links, one of said pair of links being relatively short to give maximum angular movement for a given linear movement of the operating link, and actuating means for said operating link including an eccentric, a projection connected to said operating link and adapted to engage said eccentric, said eccentric having a cutout portion whereby the eccentric engages said projection for only a portion of the total throw thereof in the direction for rendering the toggle ineffective to permit the use of said relatively short link, additional eccentric means normally ineffective while the toggle is rendered ineffective, but adapted to become effective to render said toggle effective after the limit of movement of said operating link in an ineffective direction has been reached.

13. A swaging machine having a table, means for moving said table, a support mounted in said table, said support being adapted to carry the articles to be swaged, said support having a

die in which the articles are adapted to be pressed and means for pressing said articles in said die, characterized by means whereby the movement of the table frees said articles from tight frictional engagement with said die, said last named means comprising a relatively fixed cam, one of said articles being provided with a projection in the path of said cam as said table is moved.

14. A swaging machine having a table, means for moving said table, a support mounted in said table, said support being adapted to carry the articles to be swaged, said support having a die in which the articles are adapted to be pressed, and means for pressing said articles in said die, characterized by means whereby the movement of the table frees said articles from tight frictional engagement with said die, said last named means comprising relatively fixed, spaced cams, said articles being so positioned as to enter the space between the cams during the movement of said table, one of said articles being provided with a projection adapted to engage both of said cams as said articles enter said space.

15. A swaging machine having a fixed frame and a table movably supported in said frame, a plurality of supports carried by said table, said supports being adapted to carry the articles to be swaged, each support having a bore extending substantially vertically therethrough, said bore being of such dimension as to permit one of said articles to fall freely therethrough, characterized by a track on said frame adapted to support the article on its lower end, said track terminating in advance of the swaging position to permit the swaging operation to be performed, and means adapted to be rendered effective before said track terminates for holding said article in the respective support.

16. A swaging machine having a fixed frame and a table movably supported in said frame, a plurality of supports carried by said table, said supports being adapted to carry the articles to be swaged, each support having a bore extending substantially vertically therethrough, said bore being of such dimension as to permit one of said articles to fall freely therethrough, characterized by a track on said frame adapted to support the article at its lower end, said track terminating in advance of the swaging position to permit the swaging operation to be performed, and means adapted to be rendered effective before said track

terminates for frictionally holding said article in the respective support.

17. A swaging machine having a fixed frame and a table movably supported in said frame, a plurality of supports carried by said table, said supports being adapted to carry the articles to be swaged, each support having a bore extending substantially vertically therethrough, said bore being of such dimension as to permit one of said articles to fall freely therethrough, characterized by a track on said frame adapted to support the article at its lower end, said track terminating in advance of the swaging position to permit the swaging operation to be performed, and means adapted to be rendered effective before said track terminates for frictionally holding said article in the respective support, said last named means comprising a pin for each support, the support having a lateral opening in which said pin operates, said opening extending from the outside of the support into the bore, means for normally maintaining said pin out of engagement with the article in said bore, and means adapted to become effective before said track terminates for moving said pin into engagement with the article in said bore.

18. A swaging machine having a fixed frame and a table movably supported in said frame, a plurality of supports carried by said table, said supports being adapted to carry the articles to be swaged, each support having a bore extending substantially vertically therethrough, said bore being of such dimension as to permit one of said articles to fall freely therethrough, characterized by a track on said frame adapted to support the article at its lower end, said track terminating in advance of the swaging position to permit the swaging operation to be performed, and means adapted to be rendered effective before said track terminates for frictionally holding said article in the respective support, said last named means comprising a pin for each support, the support having a lateral opening in which said pin operates, said opening extending from the outside of the support into the bore, spring means for normally maintaining said pin out of engagement with the article in said bore, and a cam adapted to become effective before said track terminates for engaging said pin and moving it into engagement with the article in said bore.
